RUSSELL L. WYSS, OF KANSAS CITY, MISSOURI, ASSIGNEE OF ONE-HALF TO DERWOOD
L. PIGGOTT, OF KANSAS CITY, MISSOURI

ELECTRIC TIMER.

1,387,223.

Specification of Letters Patent. Patented Aug. 9, 1921.

Application filed July 21, 1919. Serial No. 312,252.

To all whom it may concern:

Be it known that I, RUSSELL L. WYSS, a citizen of the United States, residing at Kansas City, in the county of Jackson and State of Missouri, have invented certain new and useful Improvements in Electric Timers; and I do declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to electric timers for ignition systems and it is particularly adapted for use in ignition systems on the present type of automobiles made by the Ford Motor Company of Detroit, Michigan, and one of the objects thereof is to provide a simple, durable and efficient electric timer which will operate with the minimum amount of attention and which is so constructed that the operating parts will be protected against deterioration on account of dust, grease and other extraneous matter.

The invention contemplates the provision of means for effecting an intimate relationship of the contacts as the movable contact passes over the stationary ones on the distributor, means being also provided to compensate for wear between the stationary contacts and the movable contact, the movable contact being preferably a spring-pressed plug or brush constantly bearing upon the distributor block, the stationary contacts being flush with the face thereof.

In the drawings,

Figure I is a disassociated view of a distributor block and commutator, and

Fig. II is a vertical longitudinal sectional view through a device constructed in accordance with my invention.

Referring now to the drawings by numbers of reference:

I designates a distributor block provided with an axial recess 2 to receive the end 3 of a commutator shaft 4 on which is a disk or commutator 5 of insulating material, the disk 5 having a lining or sleeve 6 which fits over the shaft 4 and which may be positioned thereon by a pin 7 and secured by a nut 8. The disk 5 is provided with a longitudinal recess 9 in which is a spring-pressed plug or brush 10 having movement parallel

with the axis of the shaft 4 and having a face 11 adapted to pass over the end face 12 of the block 1 and over the segmental stationary contacts 13 embedded in the block and having binding posts 14 extending therethrough to be engaged by the conductors 15 from which current is distributed to the spark plugs of the motor.

The rear end of the block 1 is provided with a projection 16 having a circumferential groove 17 to receive one edge of a casing 18, the other edge of the casing engaging a groove 19 on the block at right angles to the groove 17. The casing is substantially semi-spherical and protects the binding posts 14, and by reference to the drawings it will be apparent that the casing is provided with an opening 20 to receive a conduit 21 through which the conductors may pass to the coil box. The block 1 is provided with a lever arm 22 adapted to be engaged by a shifting lever whereby the block 1 may be partially rotated to advance or retard the spark in a well known manner.

The block 1 carries a ring or flange 23, which surrounds the commutator disk 5 and serves as a guard to protect the contacts from dust, dirt and other extraneous matter and also serves as a centering guide for the commutator disk and block 1.

When the parts are assembled as shown in Fig. II and the shaft 4 is rotated, the commutator disk will have rotative movement with respect to the block 1 and current supplied to the brush 10 through any suitable source, will pass through the several conductors 15 to the contacts 13 as the brush travels over them. For convenience, the brush 10 may be ground to shaft 4 through a ring plate 24 connected to the brush 10 through spring 10", the plate 24 bearing upon shaft 4. The spring-pressed brush will always be in contact with the end 12 of the block 1 and as the contacts are flush with the face 13 permitting the contacts to slide smoothly past one another arcing will be reduced to a minimum, if not wholly eliminated.

It will also be apparent that the spark may be advanced or retarded through the operation of the block 1 by means of the arm 22 and that the operating parts will be efficiently protected against deterioration on account of dust, oil, dirt and other extraneous matter.

What I claim and desire to secure by Letters-Patent is:

1. In an electric timer for ignition systems, a distributor comprising a block having a recessed central portion, a ring carried by the face of the block and extending outwardly therefrom, a shaft extending into the recessed central portion, a commutator disk on the shaft comprising an insulation block co-extensive with the space sealed by the ring and receivable within the ring, a spring-pressed contact parallel with the axis of the shaft and carried by the commutator disk, distributing contacts on the block having faces flush with the end thereof and in line with the circular band scribed by the contact carried by the commutator, and means for conductively connecting the commutator contact with the shaft.
2. In an electric timer for ignition systems, a distributor comprising a block having an axially located, outwardly extending portion, a housing supported by the ma-
3. In an electric timer for ignition systems, an insulation block having a recess in one face, an outwardly extending portion on the other face in line with the recess, a housing connected to the block and to the projecting portion, a commutator shaft extending into the recess, a ring-shaped member carried by the block, a commutator disk within the ring and carried by the shaft, and co-operating contacts carried by the commutator and the block.

In testimony whereof I affix my signature.

RUSSELL L. WYSS.
